AMOS SHEPARD, OF NEW BRITAIN, CONNECTICUT.

Letters Patent No. 84,714, dated December 8, 1868.

IMPROVEMENT IN MACHINE FOR BENDING SHEET-METAL.

The Schedule referred to in these Letters Patent and making part of the same.

To all whom it may concern:

Be it known that I, AMOS SHEPARD, of New Britain, in the county of Hartford, State of Connecticut, have invented a new and improved Machine for Forming Angular Tubes and Bending Sheet-Metal; and I do hereby declare that the following is a full, clear, and exact description thereof, which will enable others skilled in the art to make and use the same, reference being had to the accompanying drawings, making a part of this specification, in which—

Figure 1 is a side elevation of my invention.

Figure 2 is a front elevation of the same.

Figure 3 is a transverse section cut through line $x-x$ in fig. 2.

Figure 4 is a top view of my invention.

Figures 5 and 6 are side elevations of sheet-metal formed with this machine.

Similar letters of reference indicate like parts.

My invention consists in suspending a thin plate over the edges of two folding-bars, which bars are hinged at each end in such manner that their inner edges are in the centre of motion.

The under side of each bar is provided with a stationary support, near its outer edge, while an opening more than equal to the thickness of both bars is left under them, in such manner that when the plate and centre of the bars descend, the supports cause the bars to fold up either side of the plate.

A A designate the folding-bars, which bars are hinged at each end to slides B B, on a line with the centre of plate C.

The plate C is secured at each end to sliding posts D' D², which posts are made to slide inside of slides B B, and are rounded at their lower ends to receive a spiral spring, not shown, for raising the posts D' D² and the plate C.

One end of plate C is hinged to post D', while the other end is arranged in any proper manner, so as to be easily detached from post D², and allow one end of the plate C to be raised into position, shown by red lines in fig. 2.

E¹ designates a cross-piece, which connects the slides B B.

F F designate caps or ear-pieces, attached to cross-piece E¹ and slides B B, and supporting the ends of the pivots on which the bars A A are hinged.

At each end of the machine, one end of two spiral springs, H H, is attached to the frame G, while the other ends are connected by a rod, I, passing under the lower end of ear-piece F.

Each end of cross-piece E² is attached to the lower ends of sliding posts D' D². Thus, when the lever T is actuated, the cross-piece E² first moves, and brings down the sliding posts D' D² and plate C, until the plate C rests on the metal to be formed, and gripes it, and then causes the slides B B, and their connections with the centre of the folding-bars A A, to descend.

The outer edges of the under sides of the bars A A

rest on supports L L, which are a part of the frame G, and consequently cannot descend, but turn towards the plate C, as it descends into position, shown by red lines in fig. 3, sheet 2.

The spiral springs H H cause the slides B B and their connections to ascend, while the bars A A will fall back into their original position of their own weight.

The red lines in the several figures show the position of the several parts when the lever T is lowered.

If desired, the slides B B and their connections might be made stationary, and the frame G and its connections caused to ascend, when the machine would operate substantially the same.

a designates a gauge, which can be adjusted by set-screw b.

c c designate set-screws, which can be set to stop the slides B B and their connections, when the bars A A have folded the metal at any desired angle.

When the bars A A are caused to descend until the metal is pressed firmly against both sides of plate C, the machine forms the metal into what tinsmiths term a lock, as shown in fig. 5, sheet 2.

By raising set-screws c c, the bars A A can be stopped when they have turned the metal at a right angle.

After forming one angle, the corner of it can be placed against the gauge a, and another angle formed, and so on until four angles are formed, which will make a square tube or box, as shown in fig. 6, sheet 2.

It will then be found convenient to detach the end of plate C from post D², and raise it, as shown by red lines, fig. 2, to take the tube thus formed from the plate C.

By adjusting set-screws c c, a tube of any angle and number of sides may be formed.

K K designate tables for the convenience of the operator.

The gauge a is secured to table K, but when brought forward near plate C, it fits closely to the bar A.

The metal is then placed against it, and, as the plate C descends and gripes the metal, the metal and bars A A move away from the gauge a, and are thus allowed to form the metal closely against the plate C, which could not be done if the gauge a were fastened to bar A.

The gauge a can also be set back a distance greater than the width of the bars A A.

In all other folding-machines, I believe the gauge is connected, either with the plate or one of the bars.

By my invention I produce the first machine ever known for both forming angular tubes and turning a lock on sheet-metal. It can be operated, if desired, by the feet, thus giving the operator the use of both hands.

The gauge a is in plain sight of the operator, thus enabling him to tell by sight when the metal is against the gauge a, whereas, with the ordinary machines, he can only tell by feeling.

The plate C being suspended over the machine, the

top of which is level, a piece of metal of indefinite length can be placed under it, and a bend formed at any desired point.

Although capable of doing a greater variety of work, it can be made at as small a cost as the ordinary machines.

What I claim as new, and desire to secure by Letters Patent, is—

1. The combination of the plate C, bars A A, and supports L L, the whole connected and operating substantially as and for the purpose described.

2. The combination of the plate C, bars A A, slides B B, and set-screws c c, the whole connected and operating substantially as and for the purpose described.

3. The combination of the plate C, bars A A, gauge

a, and table K, arranged and operating substantially as and for the purpose described.

4. Hinging the plate C at one end so that the other end of the plate C can be raised, substantially as and for the purpose described.

5. The combination of the bars A A and plate C, when arranged so that at each operation of the machine the plate C shall move edgewise towards the bars A A, and gripe the metal previous to any action or movement of the bars A A, substantially as and for the purpose described.

AMOS SHEPARD.
